MACHINE FOR OPERATING UPON
SHOE PARTS

George Hazelton, Leicester, England, assignor to
United Shoe Machinery Corporation, Paterson,
N. J., a corporation of New Jersey

Application December 29, 1932, Serial No. 649,356
In Great Britain January 7, 1932

13 Claims.

(Cl. 12—51)

This invention relates to machines for operating upon shoe parts and is herein illustrated as embodied in a machine for reducing the thickness of exposed edge portions of the uppers of shoes.

5 In the manufacture of uppers for shoes it is common practice to fold over the edges of the material which forms the upper proper, i. e., the outer side which is visible in use, but when an upper is lined with leather it is frequently the practice to leave the edge of the lining in its natural unturned state, the lining being secured to the upper by stitching close to the raw unturned edge of the lining in such manner that in the finished shoe the lining edge lies slightly 10 inside the edge of the upper and can only be seen by looking into the interior of the shoe. While such unturned lining edges are thus generally unnoticeable the action of thrusting the foot into the shoe is likely to force the extreme edge of the 15 lining inwardly away from the upper thus rendering the shoe less finished in appearance. In view of the foregoing, it is an object of the present invention to provide an improved machine for operating upon the edge portions of shoe parts 20 such as shoe uppers which without sacrificing any of the characteristic advantages of such machines as heretofore constructed will be operable rapidly to reduce the thickness of edge portions 25 of such shoe parts.

30 To this end, and as illustrated, the invention provides a machine comprising a hammer and an anvil operable to press portions of the work and means for feeding the work between pressing operations, together with a gage mounted for 35 movement with the work as it is fed for locating edge portions of the work in operative position relatively to the hammer and anvil. Preferably, and as shown, the gage is located centrally of the faces of the hammer and anvil, one of such members being recessed to receive the gage during the 40 operation of the members in pressing the work. By means of the construction above outlined, work such as shoe uppers can be fed rapidly through the machine, the gage being effective at 45 all times to control the position of the work so that the pressing operations of the hammer and anvil are limited to the marginal portions thereof with the result that especially compacted edge portions are produced.

50 Other features of the invention will be apparent from the following detailed description when taken in connection with the accompanying drawing and will be pointed out in the claims.

In the drawing,

55 Fig. 1 is a side elevation of the machine con-

stituting an illustrative embodiment of the invention;

Fig. 2 is a plan view of a hammer and anvil mechanism illustrating one form of gage;

Fig. 3 is a side view of the hammer and anvil 5 mechanism;

Fig. 4 is a side view of hammer and anvil mechanism embodying an alternative form of gage; and

Fig. 5 is a front elevation of a portion of the 10 mechanism illustrated in Fig. 4 showing the hammer in depressed position.

Referring particularly to Figs. 1, 2 and 3, the machine comprises a base 10 and a work table 12 associated with which there is an anvil 14 and a 15 hammer 16 arranged for oscillation relatively to each other in pressing work such as shoe uppers. As shown in Figs. 2 and 3 the anvil 14 is formed integrally with a lever 18. The hammer 16 comprises a lever 22 mounted upon a pivot 24 on the 20 lever 18 and is provided with a laterally extending striking portion 26 arranged to project over the upper surface of the anvil 14, said portion being secured to the lever 22 by a screw 28. The lever 22 is provided with an arm 30 to which is 25 connected a link 32 arranged to impart movements of the hammer to cause it to oscillate relatively to the anvil 14.

The hammer and anvil are arranged for oscillating movement transversely of the machine between oscillations of the hammer relatively to the anvil for imparting feeding movements to work gripped between the hammer and anvil by which the work is advanced over the work table 12 by short feed-steps. To this end, the anvil 35 supporting lever 18 is mounted rigidly with a rocking sleeve 34, Figs. 1 and 5, which extends longitudinally of the frame and is secured at its inner end to the hub of an arm 36. The outer end of the arm 36 is pivoted to a link 38 the lower 40 end of which is pivoted to an arm 40 rigid upon a rocking rod 42, the ends of which are journaled in the frame. A second arm 44 on rod 42 is pivoted to the lower end of the stem 46 of a yoke 48 which embraces a cam 50 on a drive shaft 52. 45 Rotation of the drive shaft 52 results in a rocking of both the anvil and hammer transversely of the table 12.

The mechanism for oscillating the hammer 16 comprises a yoke 54 loosely mounted upon the 50 sleeve 34 and embracing a cam 56 carried by shaft 52, the lower arm of the yoke having a stud 58 loosely connected to a link 60 similarly connected to an arm 62 mounted on the hub 64 of an arm 66 which makes screw threaded connection with the 55

rod 32. The arm 62 has lugs 68 and 70 engaging portions of the arm 66 for oscillating the latter. Rotation of the shaft 52 results in the operation of the mechanism just described to effect reciprocating movements of the rod 32 to cause oscillations of the hammer 16 relatively to the anvil 14. The timing of the cams 58 and 56 is such that the work is held between the hammer and anvil during rocking movement thereof thus to advance the work 10 transversely of the feed table. The mechanisms for producing oscillations of the hammer and for carrying out the work feeding movements of the hammer and anvil are not herein illustrated in detail, and for a more complete description of 15 the construction and operation thereof reference may be had to United States Letters Patent No. 1,702,593, granted February 19, 1929, upon application filed in the name of P. R. Glass.

Means is provided for guiding work positioned 20 on the work table across the surface of the anvil. To this end the anvil is provided with a work edge guide or gage in the form of a curved pin 72 which is secured in a slot in the anvil by a set screw 74 threaded through a bolt 76 extending through the 25 anvil. The guide pin 72 is curved along the segment of a circle of radius equal to the distance of the pin from the pivot upon which the hammer oscillates. The outer side of the pin 72 can, therefore, always contact while the hammer is oscillating with the end of a slot 78 cut in the hammer to receive it. Thus the work guide 72 forms a gage 30 definitely limiting the insertion of the work between the operative faces of the hammer and anvil and is always located in fixed position relatively 35 to the forward edge of the hammer of the pin regardless of the oscillatory movements of the hammer and anvil in feeding the work.

The operative face of the hammer is plane over 40 that part of its surface which extends on either side of the slot which receives the guide pin 72. However, in front of the slot the active under surface of the hammer is beveled as shown at 80 so as to provide a striking portion comprising a surface which will be at a small angle to the operative 45 face of the anvil when the hammer is positioned close to the anvil.

Figs. 4 and 5 illustrate a modified form of construction comprising an anvil 82 having an opening 83 within which is mounted a spring pressed pin 84 which normally extends vertically from the 50 face of the anvil midway between its sides and at a short distance from its front edge (in practice about $1/8$ of an inch.) This pin acts as a guide or gage for the edge of the work similarly to the pin 72 above described, and its spring 86 allows the pin to be depressed by the contact of the face of a hammer 88 which engages the upper end of the pin which is forced downwardly until such end is substantially flush with the anvil surface when the hammer is down. The forward portion of the operative face of the hammer 88 is provided with a beveled striking portion 90 the inner edge of which lies adjacent to the gage pin 84 when the hammer is down. As shown, the 60 width of the operative face of the hammer is reduced by bevelling its leading and trailing edges 92 and 94.

When operating upon some kinds of work it is found desirable that the work be subjected to the 70 action of heat. To this end, as shown in Fig. 4 there is provided a gas jet 96 located adjacent to the hammer 88 in position for heating it.

In the operation of either of the constructions 75 above described a blank such as a shoe upper is placed lining upwards upon the work table and

one end of the edge to be pressed is entered between the hammer and anvil with said edge against the gage 72 or the gage 84. Upon operation of the hammer and anvil the work will be fed transversely of the work table step by step by the 5 hammer and anvil and the edge portions will receive a blow at each step. The operator maintains the blank in position with its edge portions in operative relation to the beveled face of the hammer by keeping the edge of the blank pressed 10 against the gage. The gage is so positioned that when the hammer is down the beveled front edge portion only of the latter projects over the work. The work thus receives a blow at a slight angle to the horizontal which effectively serves to condense the material along the edge with the result that the lining edge presents a finished 15 appearance and offers substantially no projection which would offer resistance to the insertion of a foot in the assembled shoe.

Having thus described my invention, what I 20 claim as new and desire to secure by Letters Patent of the United States is:

1. A machine for operating upon shoe parts 25 comprising hammer and anvil members, means for causing relative movement between the members to produce pressure applying operations upon work presented between the members, means for moving the members together in a direction to feed the work while the latter is engaged by said 30 members, and a gage movable with the members for locating edge portions of the work in operative position relatively to said members.

2. A machine for operating upon shoe parts 35 comprising a work table, hammer and anvil members, means for causing relative movement between said members in producing pressure applying operations upon work presented between them, means for oscillating the members while in engagement with the work to feed the work 40 across the work table, and a gage movable with one of the members constructed and arranged continuously to engage the work during the pressure applying and the feeding operations.

3. A machine for operating upon shoe parts 45 comprising a work table, an anvil associated with the table, a hammer arranged for oscillation relatively to the anvil to produce pressure applying operations upon work positioned upon the table, means for moving the anvil and hammer in a direction to feed the work along the table, and a gage mounted upon the anvil for locating edge 50 portions of the work in operative position relatively to work engaging faces of the hammer and anvil.

4. A machine for operating upon shoe part blanks comprising hammer and anvil members cooperable to press a blank presented between the members, means for causing the members progressively to feed the blank, and a gage movable with the members for locating edge portions 60 of the blank in operative relation thereto.

5. A machine for operating upon shoe parts comprising an anvil, a hammer mounted for oscillation relatively to the anvil and having therein a slot one wall of which is curved about the axis of oscillation of the hammer, and a gage pin mounted upon the anvil and having a curved portion extending within the slot in engagement 65 with the curved wall thereof.

6. A machine for operating upon shoe parts comprising an anvil, a hammer pivotally mounted for movement toward and away from the anvil and having therein a slot one wall of which is 70

- curved about the pivot of the hammer as an axis and having a beveled striking face adjacent to the slot, and a gage mounted upon the anvil and engaging the curved wall of the slot for locating edge portions of the work relatively to the beveled portion of the hammer.
5. A machine for operating upon shoe parts comprising an anvil member, a hammer member mounted for oscillation relatively to the anvil, one of said members having an opening in the face thereof within the periphery of the face, and a gage mounted upon one of the members and extending into the opening for locating work with its edge portions in operative position relatively to operative faces of the members.
10. A machine for operating upon shoe parts comprising an anvil, a hammer mounted for movement relatively to an anvil for producing pressure applying operations upon work positioned upon the anvil, the hammer having an operative face a portion of which is beveled and having a slot adjacent to the beveled portion, and a gage mounted upon the anvil and extending into the slot in the hammer for locating edge 25 portions of the work in operative relation to the beveled portion.
15. A machine for operating upon shoe parts comprising an anvil, a hammer pivotally mounted for movement toward and away from the anvil in producing pressure applying operations upon work positioned upon the anvil, the hammer having an operative face a portion of which is beveled and having a slot adjacent to the beveled
- portion, and a gage pin mounted upon an anvil and extending into the slot in the hammer for locating edge portions of the work adjacent to the beveled portion of the hammer
10. A machine for operating upon shoe parts comprising an anvil having a work-supporting face, a hammer mounted for oscillation relatively to the anvil, and a work gage mounted upon the face of the anvil for movement heightwise thereof.
15. A machine for operating upon shoe parts comprising an anvil, a hammer mounted for oscillation relatively to the anvil, and a work gage resiliently mounted upon the anvil in the path of movement of the hammer.
20. A machine for operating upon shoe parts comprising an anvil having a work-supporting face, a hammer mounted for oscillation relative to the anvil and having an operative face a portion of which is beveled, a retractable gage mounted upon the face of the anvil and so positioned as to locate edge portions of work upon the anvil in operative relation to the beveled portion of the hammer.
25. In a machine for operating upon shoe parts, an anvil having a work-supporting face, a hammer mounted for movement toward and away from the anvil, and a retractable gage mounted upon the face of the anvil and constructed and arranged to engage the hammer adjacent to its operative striking face.

GEORGE HAZELTON.
